UNITED STATES PATENT OFFICE.

JOSEPH R. HOGATE AND LEROY E. SPENCE, OF BLADEN, NEBRASKA.

FABRIC TREATMENT.

Application filed June 11, 1926. Serial No. 115,301.

The invention relates to treatment of fabric to render the same transparent or translucent for use as window lights, for instance to take the place of common glass in hot houses, chicken houses and other places where applicable, and has for its object to provide a continuous process of treatment whereby a roll of fabric may be passed submerged through a bath of beeswax yellow, paraffin and petrolatum yellow which will coat the fabric and render the same translucent.

A further object is to provide scraping bars engaging opposite sides of the fabric as it leaves the bath which will smooth the coating and scrape excess material therefrom. The bath is preferably in proportions of fifty parts of paraffin to five parts of beeswax yellow and one part petrolatum yellow.

20 A further object is to provide heating elements under the tank and means whereby the material, after the coating operation may be wound onto a roll for shipping and storage purposes.

25 With the above and other objects in view the invention resides in the combination and arrangement of parts as hereinafter set forth, shown in the drawing, described and claimed, it being understood that changes 30 in the precise embodiment of the invention may be made within the scope of what is claimed without departing from the spirit of the invention.

In the drawing, the single figure shows a 35 longitudinal sectional view through the tank, and the fabric roll in position whereby the strip of fabric may be passed through the bath in the tank, and in which figure the numeral 1 designates the frame of the device 40 and 2 the tank. The material 3 in the tank is formed from a mixture of fifty parts of paraffin to five parts of beeswax yellow and one part of petrolatum yellow. The paraffin supplies the necessary body of the fabric and 45 the beeswax yellow and petrolatum yellow give the same elasticity and prevent cracking, and the proportions set forth have been found to give the best results. Disposed beneath the tank 2 are gas burners 4, the flame 50 from which heats the tank in which the ingredients are placed and mixed and the material 3 is preferably maintained at a temperature of 50 to 60 degrees. Disposed within the tank 2 adjacent the bottom there-

of and adjacent the ends of the bottom are 55 rollers 5 under which the strip of fabric 6 passes. The strip of fabric 6 is unwound from a roll 7 and moves in the direction of the arrow *a* over the upper side 8 of the tank 2 at one end thereof, and thence downwardly into the coating material 3 under the rollers 5, and thence upwardly over the upper edge of the scraping strip 9. The strip of fabric then passes downwardly and under the scraping strip 10, which scrapes 60 the upper surface of the strip of fabric simultaneously with the scraping of the under side of the strip of fabric by the scraping member 9. The scraping operation takes place after the strip of fabric passes from 65 the bath, consequently both sides are thoroughly smoothed and scraped. The accumulating roll 11, which is provided with a handle member 12 is located a substantial distance from the bath, consequently the material will harden on the fabric before it is accumulated on the roll 11, however after the accumulating operation the roll 11 is in 70 condition to be shipped or stored. It has been found that fabric so treated when used 75 in connection with and as a window light it is water proof and weather proof, prevents cold from entering a building or house, also radiates heat from the sun's rays, consequently supplies heat to the interior of the 80 house and the radiating qualities thereof have been found to exceed that of glass. It 85 has also been found that it transmits ultra violet rays which is conducive to the health of animals, poultry, plates and human beings.

The invention having been set forth what is claimed as new and useful is:—

1. A composition of matter adapted to render fabric translucent comprising a mixture of paraffin, beeswax and petrolatum in such proportions that when applied to a fabric it will not crack and will be free of pin holes.

2. A composition of matter adapted to render fabric translucent comprising a mixture of fifty parts of paraffin, five parts beeswax, and one part petrolatum.

In testimony whereof we hereunto affix our signatures.

JOSEPH R. HOGATE.
LEROY E. SPENCE.
